UNITED STATES PATENT OFFICE.

ELMER E. PERKINS, OF CHICAGO, ILLINOIS.

DRYING KILN.

Application filed March 5, 1921. Serial No. 449,799.

To all whom it may concern:

Be it known that I, ELMER E. PERKINS, a citizen of the United States, residing at Chicago, in the county of Cook and State of Illinois, have invented certain new and useful Improvements in Drying Kilns, of which the following is a specification.

This invention relates to drying kilns, and while capable of use for drying many articles and commodities, it is especially well adapted for drying of painted or varnished articles upon which a smooth, glossy finish is desired.

In drying articles of this character, it is essential that the heated air which is circulated within the room around the articles be kept free from dust and other floating particles which would otherwise collect upon the surfaces of the articles being dried, thus detracting from the quality of the finish and luster which it is desirable to impart to such articles.

One of the primary purposes of my present invention is to provide a drying kiln in which the air will be washed and cleaned before being delivered to the drying room, and which will be so constructed that a circulation of the air within the room around the articles to be dried and an inflow of air into the room will be produced and maintained without the employment of fans or other forced draft apparatus.

Another object of the invention is the provision of means for ventilating the room to relieve it of the surplus fumes emanating from the articles being dried, which fumes, if permitted to accumulate in excessive quantities, are detrimental to the drying operation.

A further object is to so arrange the ventilating apparatus that it will in conjunction with the air supplying apparatus, maintain the requisite circulation of air within the room, and to provide means whereby the rate of circulation and the rate of delivery of the fume laden air from the room, may be regulated as desired.

Other objects and advantages of this invention should be readily appreciated as the same becomes better understood, by reference to the following description, when considered in connection with the accompanying drawings.

Referring to the drawings:

Fig. 1 is a perspective view of the interior

of a drying kiln embodying my invention; and

Fig. 2 is a similar view of a modified form thereof.

Referring to the drawings more in detail, reference character 3 indicates a plurality of walls separated by dead air spaces 4, which walls in conjunction with the air spaces form a heat-insulated drying room, in which the articles to be dried are positioned. Other preferred wall structure may be employed in lieu of that shown, if preferred.

The articles to be dried are placed in the room, and usually are run in on trucks through doors in one of the end walls of the room.

The air with which the room is supplied is delivered thereto through a conduit 5 disposed near one of the side walls thereof, and communicating with the interior of the room through a series of upwardly disposed openings 6. For the purpose of maintaining a requisite temperature within the room, I employ a plurality of steam heating coils 7, carried by brackets 8 mounted upon one of the side walls near the floor of the room. Steam in requisite quantities is supplied to the coils from any suitable source, the temperature within the room being controlled by regulating the steam supply through the instrumentality of a valve 9 disposed in the steam supply pipe, which valve is automatically controlled through suitable connections by a thermostat 11 disposed within the drying room.

It will be observed that the air inlet conduit is disposed in proximity to the heating means so that the heat applied to the conduit, in conjunction with the upwardly traveling current of air produced by the heating coils, will cause an inflow of air through the conduit without the employment of fans or other mechanical apparatus for producing a forced draft. The heating means, therefore, serve not only to maintain the requisite temperature within the drying room, but also to establish a circulation of air within the room and to induce a flow of fresh air into the room.

In order to avoid the introduction into the room of dust, dirt, and other matter which might accumulate upon the articles being dried, and thus detract from the quality of their finish, I have provided means for washing and cleaning the air prior to its introduc-

tion to the room. This means, while it may be of any preferred construction, is shown in the present instance as comprising a spray nozzle 12 disposed in a vertical leg 13 of the inlet conduit, water being supplied to this nozzle from any convenient source through a supply pipe 14. The air enters this leg through a lateral inlet opening 15, where it is subjected to the water spray which removes the dust and dirt therefrom, and the water is collected at the bottom of the leg, from which it is drained off through a drain pipe 16.

For the purpose of relieving the room of the objectionable fumes given off by the articles being dried, and further for the purpose of augmenting the circulation within the room, I employ a plurality of ventilating flues 17 which are disposed remotely 20 from the heating means and the air inlet conduit.

In the construction shown in Fig. 1, these flues are disposed adjacent the opposite side wall from the heating means and intake conduit, whereas in Fig. 2, which illustrates a double room, the ventilating flues, indicated in this instance by reference character 18, are disposed in the middle of the room, the objects to be dried being positioned at each 25 side thereof. Referring again to Fig. 1, it will be observed that each flue communicates with the interior of the room through two openings or branches 19 and 21 respectively, located at different elevations from the floor. 30 Each of these branches is provided with a damper, the spindle 22 of which is equipped with a lever 23 connected with an operating rod 24, by means of which all the dampers at one elevation may be simultaneously and 35 equally adjusted. The rate of outflow of air from the room may, of course, be controlled by regulating these dampers, and customarily, during the initial drying, when the fumes are rapidly given off from the articles and a more rapid circulation is desired, 40 the upper branches 19 are fully opened, and the lower branches 21 may be wholly or partially closed. As the drying operation progresses, it is usually found that the best results are obtained by closing the upper 45 branches 19 and opening the lower branches 21. The regulation of the dampers in the ventilating flues serves, therefore, to regulate the rate of air delivery from the room and also controls the rapidity of the circulation of air within the room.

Referring again to the construction shown in Fig. 2, it will be observed that in this instance, both side walls are equipped with 50 heating coils and air inlet conduits, while the ventilating flues 18 are disposed in the center of the room. These flues, like the flues 17, are equipped with laterally opening branches 25 and 26 respectively, disposed at different elevations, and each of

these branches is equipped with a damper connected with operating rods 27 by which the dampers may be adjusted from outside the room. The circulation of air in the room in this instance is upwardly along both 70 side walls, then downwardly in the center to the outlet branches of the ventilating flues, whereas in a single room structure, such as shown in Fig. 1, the air rises at one side of the room only and flows downwardly 75 at the opposite side.

A certain amount of humidity in the drying room being conducive to most favorable drying conditions, it is sometimes desirable to start the drying operation with the ventilating flues closed so that the moisture given off by the articles to be dried may be retained in the room, but when the fumes have accumulated to a considerable extent, it is preferable that they be relieved through 80 the ventilating flues, as previously explained. The requisite humidity is obtained from the air delivered to the room, and while the air in passing through the washing spray may be practically saturated at or near the temperature of the water, it will be manifest 85 that as soon as it enters the room where it is heated, the increase in temperature will correspondingly lower its humidity so that at no time is a condition approaching an 90 undesirable saturation point of the air obtained in the room, but on the contrary, a relatively low but desirable humidity is secured, which remains practically constant, although it is capable of slight variation by 95 regulation of the air discharge through the 100 ventilating flues.

It is believed that my invention and many of its inherent advantages will be understood from the foregoing without further 105 description, and it should be obvious that the details of construction shown and described are capable of wide modification without departing from the spirit of the invention as defined in the following claims.

I claim:

1. A drying kiln, comprising a drying room, heating means arranged at one side of said room near the floor, means for delivering air to said room above and in proximity to said heating means, means for washing said air prior to its delivery into said room, and a ventilating pipe opening into said room remote from said heating means.

2. A drying kiln, comprising a drying room, air heating means disposed at one side of said room near the floor, an air inlet conduit opening into said room above and in proximity to said heating means so that an inflow of air into said room is induced by 115 said heating means, means for washing the air prior to its delivery into the room by said conduit, and means remote from said conduit through which air is discharged 120 from said room.

3. A drying kiln, comprising a drying room, an air inlet conduit communicating with said room near one side wall thereof, means for washing the air delivered to said room by said conduit, heating means positioned below and in proximity to said conduit to induce an inflow of air through the conduit, ventilating means having a plurality of communications with said room remote from said heating means, and means for controlling the delivery of air from the room through said ventilating means.
4. A drying kiln, comprising a drying room, an air inlet conduit near one side of said room, means for washing the air delivered to the room by said conduit, heating means arranged in proximity to the conduit, a plurality of ventilating flues communicating with the interior of said room remote from said heating means, and means whereby the outflow of air from said room through all of said ventilating conduits may be simultaneously regulated.
5. A drying kiln, comprising a drying room, an air inlet conduit communicating with said room near one side wall thereof, heating means arranged below and in proximity to said conduit whereby an inflow of air through the conduit is produced, ventilating means positioned remote from said conduit, and means for controlling the delivery of air from said room through said ventilating means.
6. A drying kiln, comprising a drying room, heating pipes extending along one side wall of said room near the bottom thereof, an air inlet pipe extending along said wall above said heating pipes, said inlet pipe having a plurality of outlet openings arranged in spaced relation along said pipe, said heating means being adapted to cause an inflow of air into the room through said openings, a plurality of ventilating pipes disposed along the opposite wall of said room and provided with a plurality of openings, and means for regulating the outflow of air through said ventilating pipes.

ELMER E. PERKINS.
